UNITED STATES PATENT OFFICE.

WALTER T. JANNEY, OF PHILADELPHIA, PENNSYLVANIA.

CENTRIFUGAL CASTING MACHINE.

Application filed July 5, 1922. Serial No. 573,019.

To all whom it may concern:

Be it known that I, WALTER T. JANNEY, a citizen of the United States, residing at Philadelphia, in the county of Philadelphia and State of Pennsylvania, have invented certain new and useful Improvements in Centrifugal Casting Machines, of which the following is a specification.

My invention relates to centrifugal casting machines.

An important object in view is to provide a machine of this character with the parts so constructed and arranged that the sudden expansion of the mold which inevitably takes place when the mass of molten metal is suddenly poured into it, will not subject any of the parts to undue strain, and will not in any way affect the perfect operation of the machine.

Another object is to provide a revoluble member supporting a mold movable relatively thereto, and provided with means for yieldingly holding the mold and support in operative relation to each other.

Still another object is to provide a revoluble support carrying a mold movable relatively thereto, with means for yieldingly holding the mold and its support in operative relation to each other, with means for introducing an elastic fluid into the machine to cool the mold.

A further object is to provide a centrifugal casting machine having a revoluble support held against longitudinal movement on the machine and carrying a mold movable relatively to the support; and a ram also carried by said support and movable relatively thereto, and adapted to yieldingly hold the mold in operative relation to the support.

Another object is to provide a centrifugal casting machine having a revoluble support carrying a mold formed in sections; and having means for centering the mold relatively to the support and yieldingly holding the sections in operative relation to each other.

Still another object is to provide a centrifugal casting machine having a revoluble support carrying a mold movable relatively thereto formed in sections; and having means for simultaneously centering the mold relatively to the support and yieldingly holding the parts in operative relation to each other and yieldingly holding the

mold as a whole in operative relation to the support.

Other objects will appear in the subjoined description.

An important feature of the invention consists of a revoluble basket; a mold carried by the basket and movable relatively thereto; and electro-magnetic means for yieldingly holding the mold in operative relation to the basket.

Another important feature consists of a revoluble basket having inclined faces at one end similarly disposed relatively to the axis of revolution of the basket and a ram at its other end movable relatively to the basket and also provided with an inclined face similarly arranged relatively to the axis of revolution of the basket; and a mold formed either integral or in sections and provided at its ends with inclined faces adapted to cooperate with the inclined faces of the basket and ram respectively; and means for yieldingly pressing the ram against the mold to bring said respective inclined faces into operative relation to each other, whereby the yielding pressure of the ram against the mold simultaneously centres the mold relatively to the basket and yieldingly holds it against circumferential and longitudinal expansion therein.

The invention consists in certain novel features of construction and arrangement of parts, as will be hereinafter described and claimed, reference being had to the accompanying drawings in which:

Fig. 1 is a sectional view of my device. Fig. 2 is a side elevation of the driving pulley and the electro-magnetic mechanism carried thereby. Fig. 3 is a front elevation of the device. Fig. 4 is a similar view with the cover removed. Fig. 5 is a front-end elevation of the revoluble basket, and Fig. 6 is a side elevation thereof. Fig. 7 is a front-end elevation of the divided mold, with the parts separated from each other, and Fig. 8 is a side elevation of Fig. 7; while Figs. 9 and 10, are side and end views respectively of the casting formed by the mold illustrated in Figs. 7 and 8. Figs. 11 and 12 show a front-end and side view respectively of an undivided mold, while Fig. 13 shows the casting formed thereby; and, Fig. 14 is a side elevation of the ram.

Attention is called in the outset to the fact that centrifugal force has been employed to

yieldingly hold the lids on centrifugal casting machines, which arrangement works very well when the molds are held sufficiently upright to hold the lids in operative position on them by gravity till the machinery is speeded up sufficiently to make the centrifugal mechanism grip the lids. But for the majority of castings the molds should be disposed horizontally, in which position 10 gravity will cause the lids to fall off the molds before the machine starts revolving unless other means be provided for holding them in operative position until the centrifugal mechanism has been caused to revolve 15 with sufficient rapidity to firmly press the lids.

With my arrangement no such difficulty can exist since the mold itself is the movable part and is yieldingly held in a support 20 which serves as a guide for its movements, so that it makes no difference whether the movement be controlled by centrifugal force or springs, or any other force whatsoever. 25 Attention is also called to the fact that the yielding means which I employ for yieldingly pressing the molds, is so far removed from the molds that it is not unfavorably affected by the heat therefrom. 30 Referring further to the drawings, the numeral 1 indicates a housing having a large central opening 2 at its forward end, and at its inner end an integral sleeve 3 into which is cast a long bearing 4, which 35 supports a hollow shaft 5 having at its inner end an integral basket 6, and carrying at its outer end beyond the housing 3, a driving pulley 7.

The basket 6 is provided at its open front end with an annular outwardly extending flange 8 having four equidistant inwardly extending flange lugs 9, said lugs having inclined faces 10 on their inner sides. Loosely fitting inside the basket 6 is the mold 11 45 which may be either integral as shown in Figs. 11 and 12, or may be made in sections 12 as indicated in Figs. 7 and 8.

The integral mold is used for forming plain cylindrical castings 13, as illustrated in 50 Fig. 13, while the sectional mold is suitable for casting cylinders such as are indicated by the numeral 14 in Figs. 9 and 10, in which the cylinders have integral external rings 15.

The molds are provided around their open forward ends with inwardly extending annular flanges 16 of a depth equal to the thickness of the wall of the casting to be formed. The mold is also provided at its outer end 60 with four equidistant outwardly extending lugs 17, which have inclined outer faces 18 adapted to cooperate with the inclined faces 10 of the flange-lugs 9 of the basket 6. At their inner ends the molds are also provided with annular convex inclined faces 19

adapted to be engaged by the annular concave inclined face 20 of the ram 21 mounted in the rear end of the basket behind the mold, and having an integral tubular stem 22 extending outwardly through the shaft 5 70 of the basket. The central opening 23 of the stem 22 has the branches 24 at its inner end extending outwardly to the periphery of the ram, to connect the interior of the ram with the interior of the basket 6 around 75 the mold. At its outer end the stem 22 has a frusto-conical section 22^a, and terminates at its extreme end in a threaded section 22^b. A soft iron plate 26 having a hub 27 to add to the thickness of its central portion is received onto the frusto-conical section 22^a of the stem 22, and is jammed on said section by the nut 25.

The outer end of the ram-stem 22 has secured therein a nipple 28 to revolve with 80 said stem; and an air-tight coupling 29 connects a stationary air hose 30 with the revolving nipple 28.

The pulley 7 which is mounted on the hollow shaft 5, carries on its hub a copper 90 ring 31, which is insulated from the hub by a fibre collar 32. This copper ring, through the carbon brush 33 and wire 34 is in continuous contact with a source of direct current energy. The pulley 7 has rigidly 95 mounted thereon four soft iron cores 35 which are wound with insulated wires 36 each leading from the copper ring. These wires are wound in such a manner that the diametrically opposite cores will form magnetic poles of opposite polarity, when a direct current is passed into the copper ring 31 and thence through the wires 36 forming the coils 37 around said cores, and thence returning through the frame of the 100 machine and the wire 38 to the battery.

When a direct current is passed from the copper ring 31 through the coils 37, the cores 35 form a four-pole magnet, and as the plate 26 on the outer end of the ram stem 22 is made of magnetic material, it is drawn toward the magnetic poles, which causes the ram 21 to press the mold outwardly. A spring 39 holds the plate or armature 26 normally out of engagement 110 with the cores 35.

The cover 40 at the front of the machine has two ears 41 rigidly connected at their upper ends to a transverse shaft 42 rotatably mounted in bearings 43 at the top of the 115 housing 1. The transverse shaft 42 is provided at its ends with right-angled sections 42^a upon which are mounted the counterweights 44 for holding the cover raised when desired. A gravity latch 45 is provided for holding the cover closed when the machine is to be operated. This cover is provided at its centre with a pouring spout 46 provided with a suitable non-conducting lining 47.

The operation of the device is as follows:—Supposing the parts to be disassembled with the ram 21 forced to its farthest position to the right by the spring 39, and the cover 40 at the front of the machine closed. The latch 45 is depressed by the foot of the operator, which permits the two counterweights 44 to swing downwardly and raise the cover to open the front end of the machine. The mold is put into the basket 6 through the open front end of said basket and is turned sufficiently to bring the lugs 17 of the mold in behind the flange lugs 9 of the basket. The front cover is then drawn 15 down to its closed position and engaged by the gravity latch 45. The direct current of electricity is then turned on through the wire 34 which, according to the arrangement already described, magnetizes the cores 35 20 and draws the armature 26 toward them. This in turn forces the ram inwardly so that its annular concave face 20 engages the annular convex face 19 at the inner end of the mold and forces the mold outwardly bringing 25 the inclined faces 18 of the lugs 17 into forcible engagement with the inner inclined faces 10 of the flange-lugs 9 of the basket 6. This serves to centre the mold in the basket, and if the mold be formed in sections, as ill- 30 lustrated in Figs. 7 and 8, it will also yieldingly hold the sections in operative relation to each other. The basket is then caused to rapidly revolve by the pulley 7 which has suitable belt connection with a source of 35 power. The metal is then poured through the spout 47 into the revolving mold. At the same time compressed air is turned into the basket through the flexible hose 30 and the openings 23 and 24 of the ram connected therewith. As the mold is centred in the basket, there is a space around the circumference of the mold between the same and the basket, through which the air can freely 40 circulate to cool the mold and basket. If there is any excess metal poured into the mold, it escapes at the forward end thereof around the inner end of the spout 47 and flies out into the casing 1. The sudden expansion of the mold (both diametrically and longitudinally) which takes place when the 45 mass of molten metal is poured into it, is powerfully and yet yieldingly resisted by the magnetic pull upon the armature 26 at the outer end of the stem of the ram 21.

When the casting has solidified, the machine is stopped; the electric current and compressed air cut off; the cover 40 swung up, and the mold and casting are removed 50 from the basket with a pair of expanding tongs.

As the casting was hotter than the mold, it must contract more than the mold, and so may be easily jarred loose and slipped out of the mold; and then the above operation 55 can be repeated.

Having now described my invention, what I claim as new and desire to secure by Letters Patent is:—

1. In centrifugal casting machines, a revoluble basket; a mold carried by the basket and movable relatively thereto; a ram, the basket and ram being provided with interior inclined surfaces and the mold with exterior inclined surfaces, and means for holding the mold in coaxial alinement with the basket 75 with its inclined surfaces yieldingly pressed into engagement with the inclined surfaces of the basket and ram.

2. In centrifugal casting machines, a revoluble support; a mold carried thereby and movable relatively thereto; means for yieldingly holding the mold in operative engagement with the support; and means for simultaneously revolving the mold and for applying a current of cooling fluid thereto. 80 85

3. In centrifugal casting machines, a revoluble basket; a mold carried therein and movable relatively thereto, said basket having stops for holding the mold against movement from the basket; and a ram for 90 yieldingly pressing the mold into engagement with said stops, the basket and mold and ram being arranged in coaxial alinement with each other.

4. In centrifugal casting machines, a revoluble basket; a mold carried thereby and movable relatively thereto; a ram and electrical means for operating the same to yieldingly press the mold into operative engagement with the basket; and a spring for 100 pressing the ram in a direction away from the mold; whereby to quickly disengage the ram from the mold when the electrical current is cut off. 95

5. In a centrifugal casting machine, a revoluble basket; a mold carried thereby and movable relatively thereto; a ram for pressing the mold into operative engagement with the basket; an armature attached to the ram; and electromagnets cooperating therewith to press the ram toward the mold. 105 110

6. In centrifugal casting machines, a revoluble basket having an open end; a sectional mold carried within said basket and movable relatively thereto, a ram for yieldingly pressing the mold; the basket and ram being provided with oppositely disposed inclined surfaces; and the mold being provided with inclined surfaces adapted to be engaged by said inclined surfaces of the basket and ram, said surfaces being arranged for securely holding the sections of the mold in operative relation to each other when the mold is pressed by the ram. 115 120

7. In centrifugal casting machines, a housing open at its front end and a sleeve extending centrally from its rear end; a revoluble basket in the housing, said basket having an open front end, and a hollow shaft extending from its rear end through 125 130

- 4
- said sleeve of the housing in which it has bearing, the interior of the shaft opening into the basket; a mold in the basket movably relatively thereto; a ram mounted in 5 said hollow shaft and adapted to engage the mold; and means connected with the ram for yieldingly pressing the mold into operative engagement with the basket; and means for imparting rotation to the basket.
- 10 8. In centrifugal casting machines, a revoluble basket; a mold carried thereby and movable relatively thereto, said mold being formed of a plurality of sections; and means for yieldingly holding the sections of the 15 mold in operative relation to each other and also for yieldingly holding the assembled mold in coaxial alinement with the axis of the basket, said holding means being responsive to the force of expansion due to heat but irresponsible to the strains due to 20 the centrifugal force of the parts when the machine is in operation.
9. In centrifugal casting machines, a revoluble basket; a mold carried thereby and movable relatively thereto, a ram arranged 25 to yieldingly press the mold, the basket and ram being provided with oppositely disposed inclined surfaces, and the mold being provided with inclined surfaces adapted to be engaged by said inclined surfaces of the 30 basket and ram, said cooperating surfaces being arranged for centering the mold relatively to the axis of the basket and yieldingly holding it in operative relation thereto when pressed by the ram. 35

In testimony whereof I affix my signature.

WALTER T. JANNEY.
